UNITED STATES PATENT OFFICE.

FRANK R. MERRITT, OF HAVERHILL, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FOLDING-MACHINE.

1,258,429.

Specification of Letters Patent.

Patented Mar. 5, 1918.

Application filed August 2, 1915. Serial No. 48,153.

To all whom it may concern:

Be it known that I, FRANK R. MERRITT, a citizen of the United States, residing at Haverhill, in the county of Essex and State 5 of Massachusetts, have invented certain Improvements in Folding-Machines, of which the following description, in connection with the accompanying drawings, is a specification, like reference characters on the 10 drawings indicating like parts in the several figures.

This invention relates to folding machines and is herein illustrated in connection with a machine for folding the margins of pieces 15 of upper stock which are to be incorporated in boots and shoes.

In folding the margins of pieces of leather it has been customary to an extent to use so-called form folding machines. With machines of this type a set of forms is required 20 the contours of the operative edges of which must correspond to the contour of the margin to be folded. Thus if the machine is equipped with the proper forms to fold 25 the margin of a piece of leather of a given shape and it is desired to fold the margin of a piece of different shape, a new set of forms must be used. Inasmuch as styles of 30 shoes change frequently and most factories are making several styles at the same time, the necessity for a large number of sets of forms quickly arises. The expense, therefore, of maintaining a machine of this type 35 is considerable at best and in many cases prohibitive. The general object of the present invention is to provide a machine, which operates like a form folding machine in that it folds the whole margin at one operation, which shall nevertheless require no forms.

One feature of the invention comprises a 40 sectional table or support the sections of which are adjustable so that the operative edge of said table may be caused to assume different curves as may be desired.

Other features of the invention comprise 45 a sectional folder and a sectional knife which are similarly adjustable.

These and other features of the invention including certain details of construction and 50 combinations of parts will be described in connection with an illustrative machine and pointed out in the appended claims.

Referring now to the accompanying drawings,—

Figure 1 is a side elevation of a machine 55 in which the present invention is embodied, the treadle having been depressed just enough to unhook the latch which holds the table down;

Fig. 2 is a plan of the machine; 60

Figs. 3, 4 and 5 are detail elevations of certain parts of the machine showing the manner in which the fold is made;

Fig. 6 is a detail perspective showing the normal relation of a table section, a folder 65 section and a knife section;

Fig. 7 is a perspective showing a clamp for the work and a portion of the creaser.

The sectional table of the illustrative machine comprises a plurality of narrow bars 70 1 which are adjustable longitudinally in a carrier 3 and may be clamped in adjusted position by turning a screw 5. When it is desired to adjust the sections of the table to any given curve, for example to the curve of 75 the throat of a circular vamp, a templet of the desired shape is first made, such a templet being indicated at 7 in Fig. 2, the clamping screw is loosened the throat of the templet pressed against the rear ends of 80 the bars which form the sectional table, and the clamping screw tightened. The bars which form the table are all of the same length, and consequently the forward end of the sectional table will assume the same 85 curve which is imparted to the rear end, namely, the curve of the templet.

The folder, like the table, comprises a series of narrow sections 9 held in adjusted 90 longitudinal position with respect to one another by a clamping screw 11; and the snipping knife blades 13 are fastened to the ends of bars or sections 113 which are of the same width as the sections of the table and of the folder and are held in adjusted longitudinal 95 position with respect to one another by a clamping screw 15. The sectional knife thus formed, as well as the sectional folder, are adjusted as will presently be described by using the templet in the manner described 100 in connection with the adjustment of the sectional table or support. After the contours of the operative edges of the table, the folder and the knife have been adjusted so

that the contours of the edges of the folder and the knife are the same and are complementary to the contour of the edge of the table, the templet 7 is fastened to the lower 5 ends of the posts 17 and serves during the operation of the machine as a creaser over the edge of which the margin of the work is bent. The bars 113 which carry the knife blades 13 are provided each with a lug 213 10 against which the inner ends of the folders rest so that movement of the sections of the folder to the right, as viewed in the figures, moves the sections of the knife. Projecting downwardly from the rear ends of the knife 15 bars 113 are a series of pins 114 which, when said bars are pushed toward the front of the machine strike a stop (not shown). The purpose of this construction is to facilitate resetting of the machine. It will be noted 20 by referring to Fig. 6 that each knife bar 113 registers with a folder section and with a table section. Consequently when the bars 113 are pushed to the left the sections of the folder and of the table move with them; and 25 when the templet is placed against the other ends of the sections of the table and moved to the right to adjust the table, the folder and knife are adjusted at the same time.

Referring now to Figs. 3, 4, 5 and 6, the 30 mode of operation of the machine will be described. The sectional folder, besides its function of bending the work about the edge of the creaser, serves also as a gage to aid in positioning the work and as a shear member in conjunction with the sectional knife. 35 At its rear end each section 9 of the folder has a U-shaped end, the upper leg of which points toward the front of the machine; and each upper leg is formed with an incline 19 40 and a shoulder 21 the shoulder serving as a gage for the edge of the work to be folded, and the incline serving aside from its function of a shear member, to guide and support said edge as the work is being presented to the machine. The sections 9 at 45 their rear or right hand ends are directly beneath the bars 113 which carry the blades 13, said blades being arranged, when the folder and knife approach each other to extend between the sections of the folder. 50 As best shown in Fig. 6, each blade 13 is flat on one side and beveled on the other, also the cutting edge of the knife is inclined downwardly from the rear to the front. The 55 flat side of the blade lies close to the adjacent side of the corresponding section 9 of the folder when the folder is moved upwardly from the position shown in Fig. 3 to that shown in Fig. 4, and during this movement one edge of the incline 19 co-operates with the edge of the corresponding blade 13 to snip or slit the edge of the work.

The parts of the machine come to rest 60 with the knife, folder, and templet or creaser in the positions shown in Fig. 3.

The table 1 at this time is not in the position shown but is in lowered position to permit the work 100 to be inserted between said creaser and said table with its forward edge against the shoulder 21 of the folder. 70 The operator then steps upon a treadle whereupon the following movements and operations takes place: The table rises into the position shown in Fig. 3 thereby clamping the work against the lower ends of holding members 23, herein shown as stationary rods the lower ends of which extend through slots 25 in the creaser 7. The folder first moves up to cause the knife to slit the margin of the work and to bend the margin 80 upwardly, and then to the left to bend the margin over the edge of the creaser, the parts being then in the position shown in Fig. 4. At this point in the operation of the machine the creaser is withdrawn and 85 the folder moved downwardly to press the fold carrying the table with it the parts being then in the position shown in Fig. 5. Thereafter the folder reverses the movements which have been described until it 90 reaches the position shown in Fig. 3, while the creaser returns to its original position, the table being held in the position shown in Fig. 5 so that when the parts come to 95 rest the machine is set to permit the folded piece to be removed and an unfolded piece to be presented.

Referring now to Figs. 1 and 2 the mechanism by which these cutting, folding and pressing movements are accomplished will 100 be described. The carrier 3 in which the sections 1 of the table are mounted is pivoted at 27 to the frame of the machine and is continually urged to swing about said pivot in a direction to raise the operative 105 end of said table by a spring 29 the tension of which may be varied by turning a screw 31. A catch 33 fast to said carrier is arranged to be engaged at the proper time by a latch 35 pivoted to the frame at 37 and 110 urged to the left by a spring 39. When the machine is at rest the latch engages the catch to hold the table in lowered position. In order to trip the latch 35 so as to permit the spring 29 to raise the table, a second 115 latch 41 is pivoted at 43 to an arm 45 which is fast to a rock shaft 47, said second latch being urged to swing downwardly by a spring 49. This latch 41 engages at its outer end a pin 51 on the latch 35 and has on its 120 under side an incline 53 which strikes the end of a screw 55 to disengage the two latches at the proper time. The shaft 47 is rocked by pulling down an arm 57 one end of which is fast to said shaft. This 125 arm, when pulled down and released, serves to control a two-revolution clutch (not shown) whereby the shaft 59 is caused to make two revolutions and come to rest. The depression and release of the arm 57 is 130

brought about by depressing a treadle (not shown) on the end of a chain 61. The chain at its upper end is fast to a vertically 5 slideable rod 63 to a boss on the upper end of which is pivoted a latch 65 which engages in its downward movement a hardened plate 67 on the arm 57, a screw 69 being located to engage an incline on the end of said latch at the proper time to swing said latch to one 10 side and thereby release the arm 57. A spring 71 urges said arm upwardly at all times, but the time when this upward movement takes place is controlled by a cam 73 on which a roll 75, carried at the end of 15 said arm, runs. The arm 57 is provided with a notch 77 which, when the arm is raised, stops the shaft 59 after two revolutions have been made. Any suitable clutch mechanism may be employed and for this 20 reason the details of the present clutch have not been shown. It will be understood, however, that when the treadle is depressed the shaft 59 makes two revolutions and comes to rest. With the latch 35 in engagement 25 with the catch 33 and the latch 41 in engagement with the pin 51, the first effect of pulling down on the chain 61 will be to release the table 1 so as to permit it to rise into the position shown in Fig. 1. Further 30 downward movement of the chain will disconnect the latch 41 from the pin 51 thereby releasing the latch 35 which thereupon is returned by the spring 39 into position to engage the catch 33 again when the table 1 35 is swung downwardly by the folder 9 during the completion of the fold.

Turning now to the folder, the carrier 79 of said folder is fast to or integral with arms 81 having at their outer ends forks 40 which embrace blocks 83, said blocks being pivoted at 85 to the frame of the machine. At their inner ends the arms 81 are pivoted at 87 to an arm 89 the hub of which encircles an eccentric on the shaft 59. Consequently 45 at each revolution of the shaft 59 the folder is moved first up and then down. The pivot 87 also connects the arms 81 with an arm 91 the hub of which encircles an eccentric on the shaft 93 so that at each revolution 50 of said shaft the folder is moved first to the left and then to the right. The shafts 59 and 93 are connected by gears 95 and 97, the number of teeth on the first gear being one half that of the number of teeth on the 55 second gear so that the gear 97 makes one revolution to every two revolutions of the gear 95. The eccentrics which actuate the arms 89 and 91 are so timed with respect to each other that the folder moves up, then to 60 the left, then down. At this time the shaft 59 has made one revolution, the fold is being pressed and the table 1 has been pulled down to permit the latch 35 to engage the catch 33. During the second revolution of the 65 shaft 59 the folder is moved up, then to the

right and then down, after which the machine comes to rest.

After the folder has been moved up and to the left but before it has been moved down completely to press the fold, it is necessary 70 that the creaser 7 be drawn back from the position shown in Fig. 4 to that shown in Fig. 5. To this end the posts 17 are fixed to a slide 99 mounted in horizontal guideways in the frame of the machine. This 75 slide is connected by a link 101 with a bell crank lever 103 pivoted to the frame of the machine at 105, the horizontal arm of said lever carrying at its end a roll 107 which runs in a cam track formed on a cam carried 80 by the shaft 93.

In the operation of the machine the contours of the edges of the table, folder and knives are given the proper curvature by loosening the clamping screws 5, 11 and 15 85 and pressing the templet against the end of the table, as has been described. The clamping screws are then tightened, the templet fastened to the posts 17, and the machine is ready to be operated. As has 90 been explained, the table is normally held down by the latch 35 so as to permit the piece of leather or other stock 100 to be inserted between the templet (which now 95 serves as a creaser) and the table or support 95 1. The treadle (not shown) which is attached to the chain 61 is then depressed to pull down the arm 57. The first effect is to trip the latch 35 and allow the table 1 to rise, the parts then being in the position 100 shown in Fig. 1. The further effect is to cause the shaft 59 to make two revolutions whereby the folder and creaser are first 105 moved as shown in Figs. 3, 4 and 5 and are then caused to reverse the movements indicated in those figures. Meantime the latch 41 has been tripped by contact with the screw 55, and the latch 35 is in position to engage the catch 33 so that when the machine comes to rest there is a space between 110 the table and creaser to permit the removal of the folded piece and the insertion of the piece to be folded.

Although the invention has been set forth in connection with a particular machine, it 115 should be understood that the invention is not limited in the scope of its application to the particular machine shown and described.

Having thus described my invention, I 120 claim as new and desire to secure by Letters Patent of the United States:

1. A machine of the class described having, in combination, a table, a folder and a knife, each comprising a plurality of bars 125 adjustable longitudinally with respect to one another.

2. A machine of the class described having, in combination, a table, a folder and a knife, each comprising a plurality of bars 130

4
adjustable longitudinally with respect to one another, and means for holding said bars in adjusted position.

3. A machine of the class described having, in combination, a folder comprising a set of longitudinally adjustable bars of small cross-section, and a knife comprising a set of similar bars parallel to the first-named bars, there being on each bar of one set a projection located in the path of adjustment of a corresponding bar of the other set.

4. A machine of the class described having, in combination, a sectional table, a sectional knife, a sectional folder, and means whereby adjustment of the sections of one of the three members effects adjustment of the other two.

5. A machine of the class described having, in combination, a table comprising a plurality of adjustable sections, and a combined templet and creaser for facilitating the adjustment of the sections of the table and for determining the line of fold of the work.

6. A machine of the class described having, in combination, a table, a folder and a knife each comprising a plurality of adjustable sections, and a combined templet and creaser for facilitating adjustment of the sections of the table, folder and knife, and for determining the line of fold of the work.

7. A machine of the class described having, in combination, a table, a folder and a knife each comprising a plurality of longitudinally adjustable bars, and a templet having the contour of the edge of the work to be folded whereby pressing the edge of said templet against said bars imparts to the operative edges of the table, folder and knife the desired contour.

8. A machine of the class described having, in combination, a table, a folder, a knife

and a creaser, said table being normally 45 spaced from said creaser to permit insertion of the work, means for raising said table to clamp the work in position, and means for causing said knife and folder to snip the margin of the work and bend it over the 50 creaser.

9. A machine of the class described having, in combination, a table, a folder, a knife and a creaser, said table being normally 55 spaced from said creaser to permit insertion of the work, means for raising said table to clamp the work in position, means for causing said knife and folder to snip the margin of the work and bend it over the creaser, and means for returning said 60 table to and holding it in its normal position.

10. A machine of the class described having, in combination, a table, a folder, a knife, a creaser, said table being normally 65 spaced from said creaser to permit insertion of the work, and treadle controlled means for raising the table, causing the knife, folder and creaser to snip and fold the margin of the work and for returning 70 the table to normal position.

11. A machine of the class described, having, in combination, a work supporting member, a folding member, one of said members comprising adjustable sections, and a 75 combined templet and creaser for facilitating adjustment of the sections and for determining the line of fold of the work.

12. A machine of the class described, having, in combination, a work supporting member, a cutting member, one of said members comprising adjustable sections, and a combined templet and creaser for facilitating adjustment of the sections and for determining the line of fold of the work. 85

In testimony whereof I have signed my name to this specification.

FRANK R. MERRITT.
